UNITED STATES PATENT OFFICE.

LUCIEN CHEVANCE, OF AUXERRE, FRANCE.

DISTRIBUTING DEVICE FOR FOUR-STROKE-CYCLE INTERNAL-COMBUSTION ENGINES.

1,124,861.

Specification of Letters Patent.

Patented Jan. 12, 1915.

Application filed May 7, 1912. Serial No. 695,776.

To all whom it may concern:

Be it known that I, LUCIEN CHEVANCE, citizen of France, residing at Auxerre, Yonne, France, have invented new and useful Improvements in Distributing Devices for Four-Stroke-Cycle Internal-Combustion Engines, of which the following is a specification.

The present invention relates to improvements in distributing devices for four stroke cycle internal combustion engines, the improvements being applicable to any kind of motive fluid, such as carbureted air, steam, compressed air, and generally speaking any elastic fluid.

One of the characteristic features of the said improvements consists in arranging the ports of the distributing device, according to helices, in order to insure the maximum sectional area for the passages of the gas, and a rapid opening and closing of the said passages, this arrangement permits also the application of helicoidal segments, insulating entirely one port of the distributing device from the other and insuring a perfect tightness. Further, the said arrangement insures the forced lubrication of the distributing device.

Another characteristic feature of the said improvements consists in operating the distributing device in such a manner as, by suitably mounting the distributor upon its shaft, the periods of retardation of its movement may be caused to coincide with the periods corresponding to the opening of the passages between the distributing device and the cylinder or cylinders of the motor, while at the same time the periods of acceleration of the motion, may be caused to coincide with the periods corresponding to the closing of the said passages.

In order to facilitate the understanding of the description of the device in question, the annexed drawings represent by way of example in Figure 1 a side elevation of the principal part of the distributing device; Fig. 2 an elevation partly in section according to line II—II of Fig. 3, illustrating the application of the device to a motor having two cylinders; Fig. 3 is a sectional elevation taken on the line III—III of Fig. 2.

Throughout the various figures of the drawings, the same letters designate the same parts.

Referring to Fig. 1 of the drawings it will be seen that the distributor comprises

a hollow circular cylinder 1, on the periphery of which are formed ports such as 2 and 3. If the distributor 1 serves for controlling the admission and the exhaust of the motive fluid, it is divided into two portions *a*, *e* by an interior partition 4, of helical form which entirely separates the ports 2 and 3 from each other. The chambers *a* and *e* of the distributing device communicate respectively with the passage A, through which the motive fluid is admitted, and with the passage E corresponding to the exhaust of the cylinder or cylinders of the motor. Upon the outer periphery of the distributor 1 the ports 2 and 3 are separated from each other by a large helical segment 5. The periphery of the distributor is moreover furnished with other helical segments 6, 7, arranged in such a manner that the internal and external-lips of each port are situated as close as possible to each segment so that whatever may be the position of the distributing device one of the two segments will always form a tight closure, and there will never be communication between the admission and the exhaust compartments. The segments 6 and 7 extend to circular segments 8 and 9 arranged at right angles to the axis of the distributor. In the lower part of the compartment *a* into which the supply conduit A opens, the sleeve 1 is provided with helical blades 10, 11 which constitute a sucking and stirring device for the gas to be applied to the motor. In the upper part of chamber *e* which communicates with the exhaust conduit E, the sleeve 1 is provided with an internal stationary sleeve 12 which is secured in position by a screw plug 13. This sleeve 12 is intended to prevent the exhaust gases from remaining too long in contact with the distributing device. With this arrangement the upper part of the sleeve 1 is sufficiently cooled by the circulation of the water jacket 14 of the motor which extends over the corresponding part of the cylinder 15. The cylinder 15 of the distributor 1 is made integral with the cylinder, or cylinders, such as C' and C², of the motor, the ports 16, 17 of these cylinders terminating in helices in the cylinder 15, so as to have opposite the ports 2 and 3 of the sleeve 1 areas corresponding to these ports. The ports in the walls of the distributor cylinder, which communicate with the motor cylinders, may be disposed in the interior of the motor cylinders in such a man-

ner that each of the corresponding pistons closes the corresponding port completely at the beginning of the stroke to a degree sufficient to prevent the explosion having any effect upon the distributing device, but not sufficient to prevent the beginning of the admission at the beginning of the stroke. The piston will therefore during its descent after passing the dead point open the port by the same amount as the distributing device which has the effect of relieving the latter at the moment when the strain is greatest, without impairing the charging of the cylinder which would otherwise be the case if the port were placed lower down.

The distributing sleeve 1 is actuated in the construction shown in Figs. 1 and 2 in the following manner: The lower part α of the sleeve, is in the examples shown made integral with a shaft 18 which is connected by a universal joint 19 to a shaft 20. The shaft 20 is inclined at an angle α with regard to the shaft 18 and carries an endless screw 21 which is fixed upon the shaft and co-operates with a helicoidal gear 22 keyed upon the crank shaft M of the motor. Upon the cranks of this shaft are mounted the heads of the connecting rods B', B² connected to the pistons P', P² working in the cylinders C', C². It should be noted that owing to the shafts 18 and 20 being arranged at an angle with regard to each other, and connected by means of the joint 19, the shaft 20 will impart to the shaft 18 a non-uniform movement which comprises two periods of acceleration and two periods of retardation. By fixing the distributing sleeve suitably upon the shaft 18 one may cause the periods of retardation to correspond with the opening of the communications.

The improved device forming the subject of the present invention may be applied to motors having one, two, four or more cylinders. Figs. 2 and 3 of the drawings represented by way of example a motor having two cylinders, the pistons P' and P² of which are provided with hemispherical end faces, the ignition being effected by igniters mounted at b', b² in the covers of the cylinders. These figures also illustrate a very simple device for driving the magnets for supplying the ignition current, which permits of the dynamo being placed parallel to the main crank shaft of the motor. For this purpose the shaft 20 has keyed to it a helicoidal gear 23 which meshes with a corresponding gear 24 fixed upon the shaft 25 of the dynamo.

It should be noted that the described arrangement enables the distributing device to be rapidly dismounted, it being sufficient for that purpose to unscrew the plug 13 arranged at the top of the cylinder 15, without removing any other parts.

st. A motor constructed according to the pres-

ent invention does not present upon its casing C any outward projection or any moving part outside the casing; the casing moreover has very reduced dimensions owing to the omission of the parallel countershaft. 70

I claim:

1. Improvements in distributing devices for four stroke cycle internal combustion engines, the said improvements comprising a hollow cylindrical sleeve driven from the motor shaft; a helical partition separating this sleeve into two compartments corresponding to the admission and the discharge of the motive fluid; helical ports in this sleeve separated from each other by helical segments; circular segments provided at both ends of the sleeve and arranged at right angles to its axis, in order to insure a tight joint between the sleeve and the cylinder receiving this latter; connections between the said cylinder and the motor cylinder or cylinders; ports corresponding to those of the sleeve and insuring communication between the compartments of the sleeve and the interior of the cylinder or cylinders at the proper times, so as to insure the performance of the various phases of the cycle. 80

2. Improvements in distributing devices for four stroke cycle internal combustion engines, the said improvements comprising a hollow cylindrical sleeve driven from the motor shaft; a helical partition separating this sleeve into two compartments corresponding to the admission and the discharge of the motive fluid; helical ports in this sleeve separated from each other by helical segments; circular segments provided at both ends of the sleeve and arranged at right angles to its axis, in order to insure a tight joint between the sleeve and the cylinder receiving this latter; connections between the said cylinder and the motor cylinder or cylinders; ports corresponding to those of the sleeve and insuring communication between the compartments of the sleeve and the interior of the cylinder or cylinders at the proper times, so as to insure the performance of the various phases of the cycle; helical blades provided upon the end of the shaft of the sleeve adjacent to the admission compartment, for sucking and stirring the gas to be supplied; and an interior sleeve provided at the end of the exhaust chamber, in order, to form an extension of the distributing sleeve, and to prevent prolonged contact of the burnt gases with the latter. 100

3. Improvements in distributing devices for four stroke cycle internal combustion engines, the said improvements comprising a hollow cylindrical sleeve driven from the motor shaft; a helical partition separating this sleeve into two compartments corresponding to the admission and the discharge 125

of the motive fluid; helical ports in this sleeve separated from each other by helical segments; circular segments provided at both ends of the sleeve and arranged at right angles to its axis, in order to insure a tight joint between the sleeve and the cylinder receiving this latter; connections between the said cylinder and the motor cylinder or cylinders; ports corresponding to those of the sleeve and insuring communication between the compartments of the sleeve and the interior of the cylinder or cylinders at the proper times, so as to insure the performance of the various phases of the cycle; and suitable means for imparting to the distributing sleeve an irregular rotary

motion about its axis in such a manner that the periods of retardation of the movements imparted to the sleeve corresponds to the opening of the passages between the distributing device and the motor cylinder or cylinders, and that the periods of acceleration of said movement correspond with the closing of the said passages.

In testimony whereof I have signed my name to this specification in the presence of two subscribing witnesses.
